Inventor:

Albert P. Massey.

UNITED STATES PATENT OFFICE.

ALBERT P. MASSEY, OF WATERTOWN, NEW YORK, ASSIGNOR TO THE EAMES VACUUM BRAKE COMPANY, OF SAME PLACE.

LOCOMOTIVE-BRAKE.

SPECIFICATION forming part of Letters Patent No. 391,755, dated October 23, 1888.

Application filed February 23, 1888. Serial No. 265,000. (No model.)

To all whom it may concern:

Be it known that I, ALBERT P. MASSEY, a citizen of the United States, residing in the city of Watertown, in the county of Jefferson 5 and State of New York, have invented certain new and useful Improvements in Locomotive-Brakes, of which the following, taken in connection with the accompanying drawings, is a specification.

10 My invention relates to locomotive-brakes, and is for the purpose of maintaining an equal pressure on all the brake shoes when the brakes are on, and for holding the shoes clear from the wheels when the brakes are off.

15 Figure 1 is a view of one side of a locomotive. Fig. 2 is a cross-section of the same. Fig. 3 is a plan of the arrangement between the wheels. Figs. 4 and 5 are details of the gravity-keeper for keeping the shoe concentric with and clear from the wheel.

20 In Fig. 1, 1 is a pull-rod, which may be actuated by any of the ordinary devices for actuating brakes.

25 2 is a lever turning about a fulcrum, 3.

30 4 5 6 is an equalized lever composed of two cranks rigidly attached to a shaft that turns freely in the lower end of lever 2. (See also Fig. 2.)

35 7 is a lever for carrying the brake shoe 8. It is hung from the fixed pin 9 and connected with the crank 4 by the links 10.

40 11 is a lever for carrying the brake-shoe 12. It is hung from the fixed pin 13, and is connected by tie-bar 14 and pull-rod 15 to crank 6.

45 16 is a gravity-keeper for keeping the brake-shoes concentric with the wheels. The springs 17 are adjustable to proper position by means of the adjusting-screw 18.

50 19 is a pin that secures the gravity-keeper to the lever.

55 20 is a recess for holding spring 17.

60 The operation is as follows: The brake-shoes are shown clear from the wheels. To apply the brake, the lever 2 is drawn toward 1 by any suitable power. This causes the lower end of the lever to move in an opposite direction, carrying with it the cranked lever 4 5 6. The upper crank, 4, pushes the brake-shoe 8 against

the wheel through links 10 and lever 7, while 50 the lower crank, 6, pulls the brake-shoe 12 against the wheel through the pull-rod 15, tie-bar 14, and lever 11. The length of the cranks 4 and 6 is proportioned to the length of the levers 7 and 11, so as to give an equal 55 pressure on both brake-shoes. If one shoe was worn and the other new, or if inequalities in the track caused the wheels to vary in distance, the equalizer 4 5 6 would revolve about its axis until both shoes bore equally 60 on the wheels. The crank-arms are put at opposite ends of the shaft 5, in order that one may be directly opposite the center of the face of one wheel, while the other is in a vertical plane that is beyond the wheels, so that the 65 pull-rod 15 can pass behind the forward wheel to the forward brake-connections. A line joining the centers of pressure at the ends of the two cranks 4 and 6 passes through or near the center of the bearing in which shaft 5 revolves, and consequently the pressure from the lower end of lever 2 is distributed to the 70 brake-connections 10 and 15 without lateral stress or torsion on the lever 2. As the brake-shoes are attached to the hanging levers, which 75 support them by a pin on one side of their center of gravity, it has been found necessary to use an additional appliance to hold the shoe concentric with the wheel when the brakes are off. 16 represents such a device, in 80 which 17 is a pair of springs (one on each side of the lever) bearing against the under side of the shoe and supporting it when clear from the wheel. When the shoe is held hard against the wheel, the spring yields to any inequality, but resumes its position when the shoe is loosened. The set-screw 18 is for adjusting the spring to the shoe as the shoe wears in service. The casting 16 revolves upon the pin 19 as the set-screw is screwed in 85 or out. The springs 17 are placed in recesses 20 in the casting 16, (see Fig. 5,) and are held there securely by the lever which just fills the slot 21, Fig. 4, in the casting. They can thus be removed or replaced without trouble or 90 tools by taking out the pin 19.

95 What I claim as new, and desire to secure by Letters Patent, is—

1. In a locomotive-brake, the cranked lever 4 5 6, combined with lever 2 and brake connections 10 and 15, substantially as set forth.

2. In a locomotive-brake, the casting 16, 5 springs 17, and set-screw 18, combined with the brake-hanger 7, and shoe 8, substantially as set forth.

In testimony whereof I have signed my name

to this specification, in the presence of two sub-
scribing witnesses, on this 21st day of Febru- 10
ary, A. D. 1888.

ALBERT P. MASSEY.
